F. E. TOOTHAKER.
METHOD OF MAKING SHOES,
APPLICATION FILED FEB. 5, 1920.

1,359,636.

Patented Nov. 23, 1920.

UNITED STATES PATENT OFFICE.

FRED E. TOOTHAKER, OF SWAMPSOFT, MASSACHUSETTS, ASSIGNEE TO UNITED SHOE MACHINERY CORPORATION, OF PATERSON, NEW JERSEY, A CORPORATION OF NEW JERSEY.

METHOD OF MAKING SHOES.

1,359,636.

Specification of Letters Patent. Patented Nov. 23, 1920.

Application filed February 5, 1920. Serial No. 356,486.

To all whom it may concern:

Be it known that I, FRED E. TOOTHAKER, a citizen of the United States, residing at Swampscott, in the county of Essex and State of Massachusetts, have invented certain Improvements in Methods of Making Shoes, of which the following description, in connection with the accompanying drawings, is a specification, like reference characters on the drawings indicating like parts in the several figures.

This invention relates to the manufacture of shoes and more particularly to an improved method of making turned shoes.

In the manufacture of turned shoes it is common to make use of counters which have been previously molded substantially to final shape, such counters being used not only in turned shoes made with what are commonly called "sewed heel seats" but also in turned shoes having "nailed heel seats." In turned shoes of the type first named, the margin of the upper is sewed to the sole around the heel, before the shoe is turned right side out, by a continuation of the sewed seam which secures the upper to the sole throughout the forepart and shank. In turned shoes of the type having nailed heel seats the sewed seam which secures the upper to the sole is terminated substantially at the heel breast line of the sole, the margin of the upper at the heel being lasted over and secured by tacks. This lasting and securing may take place before the shoe is turned, in which case the overlasted upper is tacked to the sole, or after the shoe is turned, in which case the overlasted upper is usually tacked to the counter flange. The placing and attaching of the molded counter is commonly accomplished in one of two ways. According to one method it is attached while the shoe is wrong side out upon the first last, for example as shown in the patents to Thissell, No. 1,302,994 and to Connor, No. 1,302,995, the first showing a sewed seat and the second a nailed seat. According to another method the counter is placed in and attached to the shoe after it has been turned right side out as shown for example in the patent to Helming No. 1,177,516. The Helming patent shows and describes a shoe having a nailed seat, but it is also possible to insert a molded counter in a sewed seat shoe

if the lining is taken care of as set forth in 55 the Helming patent.

The present invention consists of an improved method of making molded counter turned shoes of that type in which, irrespective of how the heel portion of the 60 upper is attached to the shoe, the counter is located in the shoe after the shoe has been removed from the first last. After the upper has been attached to the sole (all the way around or part way around so as to 65 leave the heel end of the shoe open as the case may be) the shoe is turned right side out and the counter inserted and fastened in proper position. It is to the proper locating of the counter in the shoe and the 70 proper fastening of it in place that the present invention is more particularly directed.

The counter in the finished shoe lies between the upper and the lining. It should 75 be properly located both angularly and widthwise of the longitudinal axis of the shoe, and its rear end should press firmly against the inner side of the heel portion of the upper. It has been common practice to 80 insert the counter between the upper and lining, as described in the Helming patent, lay the lining down over the counter, turn its lower margin inwardly, lay a shank piece over the inturned margin of the lining, fasten it in place and then relast the shoe. In such a procedure the relasting operation including the insertion of the last, the beating out and nailing of the heel seat is depended upon to locate the counter and 85 fasten it permanently in proper position. It frequently happens, however, that the counter is improperly located by this procedure either angularly or widthwise, and that the rear of the counter is not pressed 90 firmly against the inside of the heel portion of the upper. With regard to the latter misplacement it should be remembered that, after the insertion of the second last, the lining intervenes between the counter and 100 the heel portion of the last and that the lining, being usually of fabric, is practically non-stretchable, the result being that the end thrust of the heel end of the last is largely taken by the lining and that, therefore, the counter is not forced rearwardly 105 to the extent that it should be.

According to the present invention, after

the shoe has been removed from the first last and turned right side out, and before the insertion of the second last, the shoe, together with the molded counter, is placed 5 upon an expanding form. This form may comprise a heel portion, which corresponds in shape to the heel portion of a last, and a spring-pressed toe-piece the spring being of sufficient strength to press the counter 10 firmly against the heel portion of the upper. By thus exerting a stretching action longitudinally of the shoe in the manner indicated, the heel end of the form is pressed into the counter so as to locate it properly 15 angularly, widthwise and lengthwise of the shoe. While the counter is so held it is fastened to the shoe; and thereafter the form is removed, and the shoe relasted and finished in the usual or any suitable manner. 20 In order to set forth the invention more clearly a particular procedure will now be described, but the method, as will appear in the course of the description, is not limited to the particular procedure which has been 25 illustrated.

Referring now to the accompanying drawings,—

Figure 1 shows a molded counter having attached to its inturned flange a member 30 known to the trade as a "tuck";

Fig. 2 shows a shoe wrong side out on the first last, the forepart having been sewed and the heel end lasted;

Fig. 3 shows the shoe right side out and 35 located upon the stretching form, the counter being in place and the heel portion of the lining pulled out of the way. In this figure there is also shown part of a nailing machine which may be used to fasten the 40 counter in place;

Fig. 4 shows the shoe after it has been relasted, and

Fig. 5 is a detail perspective of a portion of the shoe showing more particularly the 45 location of the nails which fasten the counter to the shoe.

The particular form of molded counter member shown comprises a counter proper 7 and a tuck 9 fastened together by staples as shown, this member being prepared 50 separately so that it may be placed in the shoe at the proper time. The particular form of counter employed and the particular construction by which the sides are prevented from spreading is immaterial so far 55 as the broader aspects of the invention are concerned, since any suitable molded counter may be used.

Assuming that a supply of suitable molded 60 counters have been provided, the manufacture of the shoe is carried out as follows: An assembled upper 11 and lining 13 and a suitable sole 15 are placed wrong side out upon the first last 17. The pulling-over 65 and lasting next takes place as usual, the

lining being slit and the heel portion pulled down as shown in Fig. 2. The upper and lining are then attached around the forepart and part of the shank portion in any suitable manner as by a sewed seam 19 as 70 shown; or, if desired, the sewing may extend entirely around the sole. As illustrated, however, the seam terminates adjacent the heel breast line, the heel portion of the upper being lasted and attached to the 75 sole by tacks 21. Instead of sewing all the way around the sole or of sewing around the forepart and shank and then lasting the heel portion as shown, the heel portion may be left open as described in the Helming 80 patent referred to above. In any event, however, the lining is slit and turned back as shown. After the temporary lasting tacks (not shown) have been removed and the seam trimmed, the shoe is pulled from 85 the first last and turned right side out.

The heel portion of the lining is now pulled partially out of the shoe so as to permit the counter to be inserted. Conveniently the insertion may be accomplished 90 by placing the counter upon the heel end of a form 23 and then placing the shoe upon the form. This form comprises a block, the heel portion of which has the shape of a last, and a toe portion which consists of a 95 toe-piece 25 pivoted at 27 to a rod 29 which is slidable in the block but held from angular movement by a pin 31 held by the block and located in a groove 33 in the rod. A comparatively stiff spring 35 which encircles the rod, bears at one end against the block and at the other end against the toe-piece, it being necessary to compress this spring to get the shoe upon the form. By subjecting the shoe, with the counter loose 100 in it, to the expanding action of the form, the shoe is subjected to a stretching action, and the rear end of the counter pressed firmly against the inside of the heel portion of the upper, the lining 13 at the heel portion of the shoe being out of the way so that the heel end of the form may contact directly with the counter, whatever stretch there may be in the upper being permitted to take place without the hindrance that 110 would take place were the lining interposed between the heel portion of the form and the upper. At the same time the counter is properly located both widthwise and angularly with respect to the upper while these 115 parts are substantially in the positions which they should occupy in the finished shoe.

With the counter thus held in proper position, the next step is to attach it to the 125 shoe. If the heel end of the shoe is left open, the heel portion of the upper may now be lasted over the counter and tacked in place, and thereafter, if desired, the sole and counter may be nailed together. With a 130

shoe like that illustrated in the drawings or with a shoe having a sewed heel seat, in either of which cases the heel end of the shoe is already closed, the step of fastening the counter in position may be accomplished by driving nails through the sole into the counter. Conveniently a nailing machine may be used having a jack spindle 37, a nail block 39 a driver 41 and a heel rest 43. In the shoe and with the machine illustrated, the attaching nails 43' pass through the truck 9 and may or may not pass through the inturned flange of the counter proper. It should be understood that neither the particular counter used nor the particular manner of attaching it to the shoe whether by lasting, nailing, both lasting and nailing or otherwise is immaterial so far as the broader aspects of the invention 20 are concerned.

After the counter has been properly located and fastened to the shoe, the manufacture of the shoe may be completed in any known manner. The illustrated shoe is removed from the form, the heel portion of the lining put into place with its lower margin inturned and overlying the margin of the tuck 9. A shank piece 45 is then placed in the bottom of the shoe and fastened by tacks. A sock lining (not shown) may then be cemented or otherwise fastened on the bottom of the inside of the shoe, such sock lining usually extending from heel to toe, after which the second last 47 is inserted and the shoe beaten out. At this time, depending upon how the counter was attached to the shoe while on the form 23, the heel seat may or may not be nailed. With the illustrative shoe no such nailing is necessary 40 since the nails 43' suffice. Thereafter the heel is attached and the usual finishing operations performed.

Although several variations of possible procedure have been indicated above, it is to be noted that each of them comprises as a step between the insertion of the first last and the insertion of the second last, the placing of the shoe with the molded counter loose in it upon an expandible form which locates the counter properly and the fastening of the counter to the shoe while it is held in proper location.

Having thus described my invention, what I claim as new and desire to secure by 55 Letters Patent of the United States is:

1. A method of making turned shoes which comprises assembling the shoe upon a last, subsequently removing this last and inserting a second last, and, between the steps of removing the shoe from the first last and inserting the second last, placing the shoe with a molded counter loose thereon upon an expandible form and while it is thereon, fastening the counter to the shoe.

2. A method of making turned shoes

which comprises assembling the shoe upon a last, subsequently removing this last and inserting a second last, and, between the steps of removing the shoe from the first last and inserting the second last, placing the shoe with a molded counter loose thereon upon an expandible form and while it is thereon, nailing the counter to the shoe.

3. A method of making turned shoes which comprises assembling the shoe upon a last, subsequently removing this last and inserting a second last, and, between the steps of removing the shoe from the first last and inserting the second last, placing the shoe with a molded counter loose thereon upon an expandible form and while it is thereon, nailing the counter to the sole of the shoe.

4. A method of making turned shoes which comprises placing an assembled upper and lining and a sole wrong side out upon a last, attaching the upper and lining to the sole, removing the shoe from the last and turning it right side out, placing the shoe with a molded counter loose thereon upon a longitudinally expanding form with the heel end of the form in contact with the counter in such manner as to locate the counter properly in the shoe and hold it in proper location, fastening the counter to the shoe and subsequently inserting a second last and finishing the shoe.

5. A method of making turned shoes which comprises placing an assembled upper and lining and a sole wrong side out upon a last, attaching the upper and lining to the sole, removing the shoe from the last and turning it right side out, placing the shoe with a molded counter loose thereon upon a longitudinally expanding form with the heel end of the form in contact with the counter in such manner as to locate the counter properly in the shoe and hold it in proper location, nailing the counter to the sole and subsequently inserting a second last and finishing the shoe.

6. A method of making turned shoes which comprises placing an assembled upper and lining and a sole wrong side out upon a last, slitting and turning back the rear portion of the lining, attaching the upper and lining to the sole at least around the forepart and into the shank, removing the shoe from the last and turning it right side out, placing the shoe with a molded counter loose thereon upon a stretching form with the heel end of the form in contact with the counter whereby the counter is properly located and held in the shoe, fastening the counter to the shoe while so held and subsequently inserting a second last and finishing the shoe.

7. A method of making turned shoes which comprises placing an assembled upper and lining and a sole wrong side out

upon a last, slitting and turning back the rear portion of the lining, attaching the upper and lining to the sole at least around the forepart and into the shank, removing the shoe from the last and turning it right side out, placing the shoe with a molded counter loose therein upon a stretching form with the heel end of the form in contact with the counter whereby the counter 5 is properly located and held in the shoe, nailing the counter to the shoe while so held and subsequently inserting a second last and finishing the shoe.

8. A method of making turned shoes 15 which comprises placing an assembled upper and lining and a sole wrong side out upon a last, slitting and turning back the rear portion of the lining, attaching the upper and lining to the sole at least around the forepart and into the shank, removing the shoe from the last and turning it right side out, placing the shoe with a molded counter loose therein upon a stretching form with the heel end of the form in contact with the 20 counted whereby the counter is properly located and held in the shoe, nailing the counter to the sole while so held and subsequently inserting a second last and finishing the shoe.

30 9. A method of making turned shoes which comprises placing an assembled upper and lining and a sole wrong side out upon a last, slitting the lining at the sides of the shoe, attaching the upper and lining 35 to the sole, pulling the last, turning the shoe right side out, pulling the heel portion of the lining partly out of the shoe, placing the shoe with a molded counter loose therein upon a two-part form the heel and toe portions 40 of which are movable apart to force the counter and shoe into proper relative positions and so to hold them, fastening the counter to the shoe while the counter and shoe are so held and subsequently inserting a second last and completing the shoe.

45 10. A method of making turned shoes which comprises placing an assembled upper and lining and a sole wrong side out upon a last, slitting the lining at the sides of the 50 shoe, attaching the upper and lining to the sole, pulling the last, turning the shoe right side out, pulling the heel portion of the lining partly out of the shoe, placing the shoe with a molded counter loose therein upon a two-part form the heel and toe portions 55 of which are movable apart to force the counter and shoe into proper relative positions and so to hold them, nailing the counter to the shoe while the counter and shoe are so held and subsequently inserting a second last and completing the shoe.

60 11. A method of making turned shoes

which comprises placing an assembled upper and lining and a sole wrong side out upon a last, slitting the lining at the sides of the 65 shoe, attaching the upper and lining to the sole, pulling the last, turning the shoe right side out, pulling the heel portion of the lining partly out of the shoe, placing the shoe with a molded counter loose therein upon a two-part form, the heel and toe portions of 70 which are movable apart to force the counter and shoe into proper relative positions and so to hold them, nailing the counter to the sole while the counter and shoe are 75 so held and subsequently inserting a second last and completing the shoe.

12. A method of making turned shoes which comprises placing an assembled upper and lining and a sole wrong side out upon a 80 last, slitting and turning back the margin of the rear portion of the lining, attaching the upper and lining to the sole, the upper all the way around the sole and the lining part way around, removing the shoe from 85 the last, turning the shoe, placing a molded counter upon a form comprising a heel portion shaped substantially like the heel portion of a last and a toe portion in the form of a spring-pressed toe piece, placing the 90 shoe on the form in such manner that the inside of the heel portion of the upper is in contact with the counter, the spring serving to hold the counter firmly against the upper and to locate the counter and shoe in proper 95 relative position, nailing the molded counter to the sole and subsequently inserting a second last and completing the shoe.

13. A method of making turned shoes which comprises placing an assembled upper 100 and lining and a sole wrong side out upon a last, slitting and turning back the margin of the rear portion of the lining, attaching the upper and lining to the sole, the upper all the way around the sole and the lining 105 part way around, removing the shoe from the last, turning the shoe, placing an assembled molded counter and tuck upon a form comprising a heel portion shaped substantially like the heel portion of a last and a toe 110 portion in the form of a spring-pressed toe piece, placing the shoe on the form in such manner that the inside of the heel portion of the upper is in contact with the counter, the spring serving to hold the counter firmly 115 against the upper and to locate the counter and shoe in proper relative position, nailing the counter and tuck to the sole and subsequently inserting a second last and completing the shoe.

120 In testimony whereof I have signed my name to this specification.

FRED E. TOOTHAKER.
